Primary Examiner — Ricky Pham(74) *Attorney, Agent, or Firm* — Fredrikson & Byron, P.A.(57) **CLAIM**

I claim the ornamental design for a swivel oval mirror with stand, as shown and described.

DESCRIPTION

FIG. 1 is a perspective view of my new design for a swivel oval mirror with stand;

FIG. 2 is a front elevation view of my new design for a swivel oval mirror with stand;

FIG. 3 is a left side elevation view thereof;

FIG. 4 is a back elevation view thereof;

FIG. 5 is a right side elevation view thereof;

FIG. 6 is a top plan view thereof;

FIG. 7 is a bottom plan view thereof;

FIG. 8 is a front perspective view thereof with all the doors open; and,

FIG. 9 is a rear perspective view thereof with all the doors open.

The broken lines shown in the drawings are for illustrative purposes only and form no part of the claimed design.
